BUTTER SLICER

Ronald R. Perkins, Dallas, Tex.

Application January 7, 1947, Serial No. 720,531

4 Claims. (Cl. 31—30)

1

This invention relates to an improved butter slicing device.

An object of this invention is to provide a device which is adapted to receive quarter pound cakes of butter in single or multiple units, and is constructed so that uniform slices of butter can be easily and quickly cut from the cake.

Another object of this invention is to provide, in a butter slicer, an improved means for progressively moving the cake of butter, the movement of the butter being effected during the initial movement of the cutter and before the cutter comes into contact with the cake.

A further object of this invention is to provide a butter slicer of this kind which also includes a pivoted closure plate at the front of the housing which is swung outwardly to open position during the initial movement of the cutter on the cutting stroke, and is returned to closed position when the cutter returns to its normal position.

A further object of this invention is to provide a slicer of this kind which is of simple construction and may be held in one hand during the operation thereof.

A further object of this invention is to provide a butter slicer of this kind in which the slicing machine as well as the butter content may be placed within an iced or refrigerated cooler in such a way that sliced butter may be obtained from the machine while the butter remains cooled and/or refrigerated. The butter slicing machine may fit into slots or apertures in the cooler or in some other way or manner situated so that the operator may obtain sliced butter simply by actuating the cutting mechanism and will not necessitate the holding of the butter cutting machine in the hand.

With the above and other objects in view, my invention consists in the arrangement, combination and details of construction disclosed in the drawings and specification, and then more particularly pointed out in the appended claims.

In the drawings,

Figure 1 is a detail side elevation, partly broken away and in section, of a butter slicing device constructed according to an embodiment of this invention.

Figure 2 is a detail front elevation of the device.

Figure 3 is a longitudinal section through the device.

Figure 4 is a sectional view taken on the line 4—4 of Figure 1.

Figure 5 is a sectional view taken on the line 5—5 of Figure 1.

Figure 6 is a fragmentary sectional view,

2

similar to Figure 3, showing the cutter at substantially the end of its cutting cycle.

Figure 7 is an enlarged fragmentary side elevation, partly in section, showing the feeding means for moving the butter through the housing,

Figure 8 is a fragmentary sectional view taken on the line 8—8 of Figure 4,

Figure 9 is a fragmentary sectional view taken on the line 9—9 of Figure 2,

Figure 10 is a fragmentary side elevation on an enlarged scale and partly in section, showing the cutter and the closure operator,

Figure 11 is a fragmentary sectional view taken on the line 11—11 of Figure 4,

Figure 12 is a fragmentary bottom plan of the follower and ratchet for moving the follower.

Referring to the drawings, the numeral 15 designates generally an elongated tubular housing which is substantially square in transverse section. The housing 15 includes top and bottom walls 16 and 17 respectively, and opposite side walls 18 and 19. The housing 15 has slidably disposed therein a follower 20 in the form of a polygonal plate which is secured to an elongated

25 toothed bar 21 by means of a connecting member 22. The connecting member 22 extends loosely through an elongated slot 23 which is formed in the upper portion of the side wall 19. The toothed bar 21 is protected by means of a substantially L-shaped shield 24 which is fixed at one side thereof to the top wall 16 and extends laterally therefrom with the other side thereof in depending vertical position.

The cake or block of butter which is to be sliced is disposed in the housing 15 and the follower 20 engages against the rear end of the cake of butter.

When the follower 20 moves forwardly under the action of the operating means as will be herein-after described, a portion of the cake of butter will be projected beyond the forward end of the housing 15. A horizontally disposed cutter 25 is fixed to a pair of vertically disposed cutter

35 supporting rods or bars 26 which, at their upper ends, are formed with bent portions 27 secured to the bight 28 of a U-shaped slide, generally designated as 29. The slide 29 includes vertical legs 30 which are slidably disposed in tubular guides 31 and 32 which are fixed to the forward ends of the side members 18 and 19 respectively.

45 The cutter slide or carrier 29 is constantly urged upwardly by means of springs 33 engaging about the legs 30 and bearing at their lower ends against the top wall 16 and at their upper ends against shoulders 34 which are formed at the upper ends of the slide bars 30. The cutter 25 is

constructed in the form of a taut piece of wire which is stretched between the lower ends of the cutter supporting bars 26. One of the cutter supporting bars 26 has fixed thereto an elongated closure operating rod or bar 35. The bar 35 is disposed at the forward side of one of the bars 26 and is formed at its lower end portion with upper and lower teeth or lugs 36 and 37 respectively.

A notch 38 is formed in the rod 35, adjacent the upper side of the upper lug 36, the purpose for which will be hereinafter described. A closure, generally designated as 39, is pivotally carried by the forward end of the housing 15. The closure 39 is constructed in polygonal form and includes a forward wall 40, upper and lower walls or flanges 41 and 42, and opposite side walls 43. When the closure 39 is in closed position, as shown in Figure 3, the walls 41, 42 and 43 will be in alignment with the adjacent walls of the housing 15.

The wall 40 is offset forwardly from the forward end of the housing 15 so that when the follower 20 initially moves the cake of butter forwardly, the uncut projecting end of the butter may engage within the closure or cap 39. The closure or cap 39 has secured thereto a pair of ears or arms 44 which extend forwardly and upwardly from the forward wall 40. The guides 31 and 32 have fixed thereto upwardly extending ears 45 and 46 respectively, through which a shaft or pivot member 47 loosely engages.

The ear 44 on the side of the closure 39 which confronts the side wall 19 is formed with a lug 48, which in the closed position of the closure, is adapted to engage between the teeth or lugs 37 and 36, as shown in Figure 3. The upper end of the ear 44, bearing the lug or tooth 48, is slightly rounded, as indicated at 49, so that this rounded corner portion of the ear 44 may engage within the notch 38 at the time the closure 39 swings outwardly and upwardly to open position. The straight upper edge 50 of the ear 44 is adapted, when the closure 39 is in open position, to substantially contact with the forward side of the bar 35 and thereby hold the closure 39 in open position.

In order to provide for the progressive movement of the follower 20 and the toothed rod 21 during the initial downward movement of the cutter 25, and before this cutter contacts with the butter, I have provided a spring-pressed pawl 51 which is pivotally carried, as at 52, on an L-shaped lever 53. A stop lug or member 54 is fixed to the outer side of the housing wall 19 and is adapted to limit the rearward swinging of the pawl lever 53. The lever 53 is pivoted, as at 55, to the side wall 19, being constantly urged to swing upwardly and rearwardly by means of a spring 56. The pawl lever 53 is adapted to be rocked forwardly and downwardly upon downward movement of the cutter and the carrier by means of a second pawl 57 which is pivotally mounted, as at 58, on the vertical leg 59 of an L-shaped pawl carrier 60.

The pawl carrier 60 includes a lower horizontal leg 61 which is formed with an eye or sleeve 62 engaging about one of the vertical slide bars 30, and fixed thereto by means of a pin 63. The pawl or dog 57 is constantly urged to operative position, projecting rearwardly of the rear edge of the supporting member 59, by means of a spring 64. The pawl or dog 57 is adapted to engage a laterally projecting member 65 carried by the L-shaped pawl lever 53, engaging the upper side of

the lug 65 when the cutter carrier is in its uppermost position.

When the carrier 29 is moved downwardly, the bill of the dog 57 will swing the horizontal side 66 of the pawl lever 53 downwardly and the bill of the dog 57 will then ride off of the lug 65 so that the toothed bar 21 will only be moved forwardly for substantially one tooth or division thereof. A stop member 67 is fixed to the pawl lever 53 and is adapted to limit the movement of the pawl or dog 51, as shown in Figure 1.

In the use and operation of this device, a cake of butter which is preferably square in transverse section, and which may be a quarter pound of butter, is inserted in the rear end of the housing 15, feeding bar 21 with follower 20 being moved rearwardly to a position which will permit the insertion of the butter for the entire length thereof in the housing 15. This may also be accomplished by moving the cutter 25 downwardly to swing the closure 39 in its open position and inserting the cake of butter through the forward end of the housing.

The cutter 25 is pushed downwardly, being normally disposed a substantial distance above the top of the housing 15. During the initial cutting stroke of the cutter 25, the closure 39 will be swung forwardly and upwardly to the position shown in Figure 6, by engagement of the tooth 36 with the closure operating lug 48. At the same time and before the cutter 25 comes into contact with the butter, dog 57 will rock pawl lever 53 forwardly, dog 51 being held by means of the stop 67 against rearward swinging. This will progressively move the follower bar 21 forward for at least one tooth or division of the bar 21. Further downwardly movement of the cutter 25 by pressure on the carrier 29 will cause dog 57 to ride off of lug 65 and at this time pawl lever 53 will swing rearwardly against stop 54 which is the normal position of this lever. Cutter 25 may then be moved downwardly through the butter which will drop from the forward end of the housing 15.

With a construction as hereinbefore described, a cake of butter may be cut in even slices at a rapid rate, and the thickness of these slices will be determined by the extent of the progressive movement of follower 20.

I do not mean to confine myself to the exact details of construction herein disclosed, but claim all variations falling within the purview of the appended claims.

What I claim is:

1. A slicing device comprising a tubular housing, a cutting member, a carrier for said member, means slidably mounting said carrier at one end of said housing whereby said cutting member may be moved across said one end, a follower in said housing, an elongated toothed bar fixed to said follower, an L-shaped lever rockably carried by said housing, a spring-pressed dog carried by one leg of said lever, engageable with said bar, and a laterally projecting lug carried by the other leg of said lever, and a second spring-pressed dog carried by said carrier engageable with said lug whereby said lever will be rocked to advance said bar during the initial movement of said carrier on the cutting stroke thereof.

2. A slicing device comprising a tubular housing, a cutting member, a carrier for said member, means slidably mounting said carrier at one end of said housing whereby said cutting member may be moved across said one end, a follower in said housing, an elongated toothed bar fixed to said

follower, an L-shaped lever rockably carried by said housing, a spring-pressed dog carried by one leg of said lever, engageable with said bar, and a laterally projecting lug carried by the other leg of said lever, a rearwardly projecting member fixed to said carrier, and a second spring-pressed dog carried by said latter member engageable with said lug whereby said carrier will be rocked to advance said bar during the initial movement of said carrier on the cutting stroke thereof.

3. A slicing device comprising a tubular housing, an inverted U-shaped carrier including downwardly extending legs, means engaging said legs for slidably mounting said carrier at one end of said housing, a cutter carried by said carrier and movable across said one end of said housing, springs disposed about said legs constantly urging said carrier to normally dispose said cutter in spaced relation to the plane of the top wall of said housing, a closure swingably carried by said housing at said one end, closure operating means carried partly by said carrier and partly by said closure, whereby said closure will be moved to open position during the initial movement of said carrier on the cutting stroke thereof, and means correlated with said housing and said carrier for advancing the article in said housing simultaneous with the initial movement of said carrier.

4. A slicing device comprising a tubular housing, an inverted U-shaped carrier including

downwardly extending legs, means engaging said legs for slidably mounting said carrier at one end of said housing, a cutter carried by said carrier and movable across said one end of said housing, springs constantly urging said carrier to normally dispose said cutter in spaced relation to the plane of the top wall of said housing, a closure swingably carried by said housing at said one end, closure operating means carried partly by said carrier and partly by said closure, whereby said closure will be moved to open position during the initial movement of said carrier on the cutting stroke thereof, said closure operating means including a pair of spaced teeth carried by said carrier, and a lug carried by said closure engageable between said teeth, and means correlated with said housing and said carrier for advancing the article in said housing simultaneous with the initial movement of said carrier.
